UNITED STATES PATENT OFFICE

TULLY DE STEFANI, OF CHICAGO, ILLINOIS, ASSIGNOR, BY MESNE ASSIGNMENTS, TO THE LIQUID CARBONIC CORPORATION, OF CHICAGO, ILLINOIS, A CORPORATION OF DELAWARE

COOLER CABINET FOR SODA FOUNTAINS

Application filed April 3, 1925. Serial No. 20,375.

This invention relates to improvements in cooler cabinets for soda fountains and the like and its purpose is to provide an improved cabinet having receptacles for containing ice cream and other materials adapted to be maintained at a low temperature. The principal object of the invention is to provide a cooler cabinet having a receptacle adapted to be closed by an improved form of cover capable of being removed to permit the insertion and withdrawal of containers for ice cream and the like and having lids which permit access to the said containers for withdrawing ice cream therefrom. A further important object of the invention is to provide an improved cover having improved means for preventing the passage of heat to the interior of the cooler box. Still another object is to provide a cooler cabinet having a cover formed of molded heat insulating material provided with hinged or removable lids capable of being elevated to permit access to the interior of the box. Other objects relate to various features of construction and arrangement which will appear more fully hereinafter.

The nature of the invention will be understood from the following specification taken with the accompanying drawings in which one embodiment is illustrated. In the drawings, Figure 1 shows a partial top plan view of a cooler cabinet embodying the features of the present invention, illustrating the improved cover with parts thereof broken away; and Fig. 2 shows a transverse vertical section taken on the line 2-2 of Fig. 1.

As illustrated in the accompanying drawings, the invention is shown as being embodied in the cooler box 10 of a soda fountain having containers 11 for fruit juices and the like extending upwardly from one edge thereof and having the usual counter 12 extending horizontally adjacent the upper edges of the containers 11. At the end of the box 10 there is an upwardly extending wall 13 around which the counter 12 may be extended. The cooler box 10 has a metallic rear wall 14 and a metallic capping 15 extends horizontally from the upper edge of the wall 14 forming the flat top surface of

the cooler box. The top capping 15 is projected upwardly to form a flange or rib 16 extending along the rear edge of the box to prevent the overflow of water and the like which may collect on the upper surface of the capping, and a flange 17 extends downwardly from this rib, overlapping the rear wall 14. The cooler box is provided with one or more inner receptacles 18, each having a metallic wall which is preferably substantially oval in cross-section. The top capping 15 is provided with an opening 19 of similar oval shape, the metal of the capping being projected upwardly to form an annular bead 20 around the opening 19 which is formed within the depending flange 21. The flange 21 is adapted to extend downwardly within the wall of the receptacle 18 and this wall terminates below the top capping 15 so that a metallic contact of the capping with the wall of the receptacle is prevented. A mechanical connection is made between the receptacle 18 and the flange 19 by means of an annular strip 22 of heat insulating material which extends upwardly within the bead 20 and is interposed between the flange 19 and the receptacle 18, as shown in Fig. 2. This novel means for preventing the transfer of heat from the top capping to the wall of the receptacle is claimed in my co-pending application Serial No. 540,635, filed March 2, 1922. The spaces beneath the top capping 15 and around the wall of the receptacle 18 are filled with heat insulating material 24.

The receptacle 18 of oval cross-section is adapted to receive two ice cream containers 25 which are of cylindrical form and which are inserted into the receptacle 18 through the top opening 19. Owing to the desirability of using containers 25 of large capacity and to the limited width of the cooler box which is usually permitted in a direction parallel to the long axis of the oval opening 19, it is frequently impossible to provide the top capping with an opening large enough to permit the independent insertion or withdrawal of either container 25, particularly where the container 11 for fruit juices and flavors extends upwardly from the inner

edge of the top capping, as illustrated in the drawing. The present invention therefore provides the top capping with an opening 19 of elliptical form in which the long axis of the ellipse is shorter than the long axis of the elliptical cross-section of the receptacle 18, so that the receptacle 18 extends beneath the top capping at the rear edge of the opening 19 and some distance to the rear thereof, the wall of the container 18 being provided with a horizontally extending portion 18^a spaced from the top capping 15. The transverse dimension of the opening 19 is sufficient to permit the insertion or withdrawal of either container 25 and after one of these containers has been placed in the receptacle 18 it is moved inwardly beneath the wall section 18^a to permit the insertion of another container 25.

20 The opening 19 in the capping 15 is normally closed by a cover 27 the major portion of which is formed preferably of a molded heat insulating material such as "Bakelite." The cover 27 is elliptical in form and is provided with an annular overhanging flange 28 adapted to overlie and contact closely with the bead 20 which is formed on the top capping 15 around the opening 19. An annular depending flange 29 of the cover 27 extends downwardly within the opening 19 so that the lower edge of the cover is substantially flush with the lower surface of the wall section 18^a of the receptacle 18. The cover 27 is provided with two openings 30 which are separated by the transverse bridge member 31 formed as an integral part of the cover. The walls of the openings 30 adjacent the bridge member 31 extend parallel to each other transversely of the cover and the remaining portions of the walls of the openings 30 have substantially the same curvature as the outer peripheral portions of the cover 27. The openings 30 are closed by lids 33 each made up of a body portion 34 of heat insulating material, preferably "Bakelite" or the like, this heat insulating material being covered by a metallic sheet 35 of nickel, silver, or the like, preferably the same material of which the top capping 15 is constructed. The 40 cover 27 is provided with an annular bead 36 extending upwardly around each of the openings 30 and each of the covers 33 is provided with an annular flange 37 which overhangs and fits closely the bead 36 of its opening. 50 The metal sheet 35 of each lid is extended downwardly around the outer edges of the lid as shown at 38 and the "Bakelite" 34 or other material is preferably molded within the metallic sheet 35 so that a rigid construction is obtained. The transverse bridge member 31 of the cover 27 has embedded therein a pair of upwardly extending posts 39 each adapted to carry at its upper end a horizontally extending pivot pin 40 adapted to be engaged by hinge members 41 which are embedded in

the "Bakelite" of the lids 33 and which permit the two lids 33 to be swung upwardly toward each other for permitting access to either of the containers 25. A handle 43 is provided on each lid 33, the stem 44 of each handle extending downwardly and being embedded in the "Bakelite" 34 of the lid.

By means of this construction, the attendant at the soda fountain or the like may readily obtain access to either container 25 within the receptacle 18 by lifting the lids 33 about their hinges. This is permitted by the novel arrangement of the opening in the top capping and the novel construction of the lids provided in the cover. The construction of the cover of molded heat insulating material prevents the transfer of heat to the walls of the receptacle 18 and the container 25 and substantially prevents the accumulation of moisture on the top surfaces of the cooler box. The construction of the lids of metal and heat insulating material provides great strength for the parts which are frequently manipulated by the attendant and adds greatly to the attractive appearance of the top surface of the cabinet. The provision of upwardly extending annular beads and overhanging flanges on the lids and the cover provide a tight closure which prevents the access of moisture or foreign material to the interiors of the containers 25.

Although one form of the invention has been shown and described, it will be understood that it may be constructed in various other forms within the scope of the appended claims.

I claim:

1. A cooler cabinet for soda fountains having a flat metallic capping provided with an opening therein and having an upwardly extending bead around said opening, a cover having an annular part of molded heat insulating material projecting over and contacting with said annular bead, said cover having an aperture therethrough, a bead extending upwardly around said aperture, and a lid for closing said aperture having a part extending outwardly and contacting with said bead.

2. A cooler cabinet for soda fountains having a receptacle therein, a top capping having an opening over said receptacle, a cover for said opening having a frame structure formed of molded "Bakelite" adapted to contact directly with said top capping, said cover having an aperture therethrough, a post embedded in said "Bakelite," a molded lid heat insulating for closing said aperture, and a hinged member embedded in said lid and pivoted on said post.

3. A cooler cabinet for soda fountains having a receptacle therein, a top capping having an opening over said receptacle, a cover for said opening having a frame structure formed of molded "Bakelite" adapted to con-

tact directly with said top capping, said cover having an aperture therethrough, a post embedded in said "Bakelite," and a lid hinged on said post for closing said aperture, said 5 lid comprising a metallic cover plate having a downwardly extending annular flange within which is molded a body of "Bakelite".

4. A cooler cabinet for soda fountains having a flat metallic capping provided with an 10 opening therein, a cover having an annular part of molded heat insulating material projecting over and contacting with said capping around said opening, said covering having an aperture therethrough, a bead 15 extending upwardly around said aperture, and a lid for closing said aperture having a part extending outwardly and contacting with said bead.

5. A cooler cabinet for soda fountains having a receptacle therein, a top capping having 20 an opening over said receptacle, a cover for said opening having a frame structure formed of molded heat insulating material having a smooth outer surface and adapted 25 to contact directly with said top capping, said cover having an aperture therethrough, a post embedded in said heat insulating material, a molded heat insulating lid for closing 30 said aperture, and a hinged member embedded in said lid and pivoted on said post.

6. A cooler cabinet for soda fountains having a receptacle therein, a top capping having 35 an opening over said receptacle, a cover for said opening having a frame structure formed of molded heat insulating material adapted to contact directly with said top capping, said cover having an aperture therethrough, a post embedded in said molded heat insulating material, and a lid hinged 40 on said post for closing said aperture, said lid comprising a metallic cover plate having a downwardly extending annular flange within which is molded a body of heat insulating material.

45 TULLY DE STEFANI.
